UNITED STATES PATENT OFFICE.

RALPH R. ROOT, OF NOTTINGHAM, OHIO.

INCUBATOR.

1,192,565.

Specification of Letters Patent. Patented July 25, 1916.

Application filed February 18, 1909. Serial No. 478,654.

To all whom it may concern:

Be it known that I, RALPH R. Root, a citizen of the United States, residing at Nottingham, in the county of Cuyahoga and State of Ohio, have invented a certain new and useful Improvement in Incubators, of which the following is a full, clear, and exact description, reference being had to the accompanying drawings.

10 My invention relates to incubators, and has for its object the provision of an incubator in which the eggs derive their warmth by being maintained in contact with a heat radiating device, throughout their 15 period of incubation. Furthermore, it comprises a casing which is so constructed as to be easily assembled and taken apart, and allowing access to the various parts of the incubator without dismantling the entire 20 casing.

Generally speaking, the invention comprises the elements and combinations thereof of set forth in the accompanying claims.

Reference should be had to the accompanying drawings in which—

Figure 1 is a central section of the incubator casing with the heater removed; Fig. 2 is a central vertical cross section of the incubator; Fig. 3 is a perspective view 30 of the incubator casing; Fig. 4 is a plan view of the shelf; Fig. 5 is a cross section of a shelf showing the means for preventing the eggs from rolling off; and Fig. 6 is a sectional view of a portion of the incubator 35 showing the relative positions of the shelves with respect to the heating device and also showing the curtains.

The casing comprises a base 1, the end portions of which are triangular in form at 40 their upper portion, the apex of the triangular portions being hollowed slightly for the purpose of receiving the ends of a heat radiating device 2, which, as will be seen from Fig. 2, occupies a central position with 45 relation to the incubator casing. The heat radiating device in this instance is comparatively thin when considered with respect to its length and height, and maintains a vertical position in the incubator.

50 The lower portion of the heat radiating device is supported on the end portions of the base 1, and suitable means are provided for maintaining the tank in an upright position independent of the side portions of the incubator which are adjacent to it. In the instance shown, the heat radiating device is

a hot water tank having a pipe 3 running through the lower portion thereof, which pipe is the part actually supported by the ends of the base portion 1. This pipe communicates with a drum 4. A pipe 5^a communicates with the lower portion of the tank independent of the pipe 3 and its opposite end is in communication with a drum 5, the drums 4 and 5 being in communication by one or more pipes 6. A shield 7 depends from the upper drum 4 and extends downwardly nearly to the top of the drum 5, leaving a slight space between the lower edge of the shield and the drum 5. The drums 4 and 5 are provided with walled central openings, the central opening in the drum 5 being adapted to receive the burner of any suitable heating device, by means of which the water is heated, which causes circulation of the warm water through the tank 2. A suitable regulating device will be provided for governing the amount of heat supplied to the drums 4 and 5, thereby regulating the temperature of the water within the tank 2.

The pipe 5 engages with a slot formed in one of the end portions of the base 1 so as to prevent the tank 2 from tipping and hold the same in a vertical position. However, it will be apparent that the specific form of heat radiating device herein shown and above described is not the only form which might be employed in an incubator of the construction which is shown and described, and therefore I do not limit myself to this form, and any suitable means for holding the heat radiating device in an upright position is within the scope of this invention.

Upon the base 1 is supported the upper part of the incubator which comprises symmetrical half portions 8 and 9. Each half is secured to the base portion by means of hinges 10 and the lower portion of each half is formed with a slanting lower edge to conform to the contour of the end members of the base.

The outside portion of each half is formed with a removable closure 11 and 12, which closures are hingedly secured upon the lower part of the incubator casing, by means of hinges 13. The two halves 8 and 9 of the incubator are held together by a suitable catch represented at 14, and each of the closures 11 and 12 is held in place with respect to the half portions 8 and 9 by means of suitable catches 15.

Within the incubator the end walls of the upper parts of the casing 8 and 9 are formed with a series of downwardly and inwardly slanting grooves which are adapted to receive shelves 16. These shelves may extend from end to end of the incubator, or, if desired, vertical partition members may be placed within the casing at different points, which partition members will be grooved in the manner correspondent to the groove in the end walls to receive one end of a shelf to support the same.

Upon each shelf member is mounted a device for preventing the eggs from rolling off the shelf when one of the half portions of the incubator is open. This device comprises an angular rail member 17 which has end portions, each end portion being provided with a downwardly projecting stud 18 formed with a head. The shelf is formed near each of its ends with a slot 19, which is provided with a rounded portion of larger diameter at one end thereof. In assembling the member 17 with respect to the shelf 16, a stud 18 at one end of the member 17 is inserted through the round portion of one of the slots 19 and pushed as far into the slot as it will go, at which time the stud at the opposite end of the member 17 is in a position to enter the end of the round portion of the slot 19 at the opposite end of the shelf, and the member 17 is then moved until the members 18 at both ends thereof occupy positions within the slots 19. When the shelf is inserted into its proper position in the incubator, the end walls of the member 17 will engage with the end walls of the casing, and the member 17 will be prevented from lateral movement.

Upon the lower part of each shelf and depending therefrom is a curtain 20, which, as shown in Fig. 6, comprises a strip of suitable material, the outside edges of which are secured to the edges of the shelf. In the instance shown in Fig. 6, the shelf 16 is formed of metal and the edges thereof are bent inwardly upon themselves, and the edges of the curtain 20 are held thereby.

Each shelf is provided with a device for rolling the eggs, which device comprises a strip of cloth 21, the edges of which are sewed together so as to form a sleeve or endless belt which is slipped over the shelf and extends substantially the entire length of the shelf between the position occupied by the studs 18 at the opposite ends thereof and beneath the rail 17. The cloth 21 will therefore lie flat with the top of each shelf and will surround and hang below each curtain 20. The eggs being placed upon the shelf and lying upon the upper part of the shelf 16 may be rotated by grasping the portions of the sleeve 21 which are toward the outside thereof and pulling the same in a manner easily understood, whereby the egg

will be rotated so as to change this point of contact with the heating device, and yet the egg will not be removed from its contact with the heat radiating device. Access to the sleeves 21 is obtained by opening either of the closure members 11 or 12 according to which side of the casing the eggs to be rotated are situated. The eggs being placed upon the shelves will press the curtain 20 and sleeve member 21 outwardly, as shown at the lower part of Fig. 6, thereby preventing too rapid circulation of air around the egg, and yet allow the free passage of air below the curtain so that air from the outside atmosphere, fresh and moist, may at all times have access to the interior of the incubator and circulate around the eggs, thus simulating the feathers of a hen sitting on her eggs.

It will be observed that the egg is in contact with the heat radiating device at substantially one point *a*, which point is upon one side of the egg, but the heat in passing through the egg will follow a course generally represented by the lines *a*—*b*; and it has been found that a portion of the egg above the dotted line *a*—*b* will always be subjected to the heat carried from the heating device, and that the temperature of such portion of the egg will be sufficient to start and carry on incubation. This condition of affairs closely approximates the conditions which are extant when a hen is sitting on her eggs, for her body being soft, the eggs will press the body inwardly, thereby covering a portion of the surface of the egg and keeping the same in contact with the body.

In every fertilized egg, the life germ within will, because of its light specific gravity, always occupy a position at the top of the egg no matter in what position the egg may lie, and furthermore, it is known that the life germ has a great affinity for heat and when heat is applied to a fertilized egg at any given point, the life germ tends to migrate to such point. If heat be applied to an egg at the top thereof and the point of application of the heat approximately corresponds with the position of the life germ, there is no migration of the germ; however, the germ is drawn close to the shell under influence of the heat, and unless the egg is frequently rotated the germ will become attached to the shell, which will make the egg worthless.

In applying the heat at a point upon the side of the egg, the life germ will occupy a position somewhere midway between the top of the egg and the point of application of the heat and furthermore the germ will be drawn somewhat toward the interior of the egg and away from the shell, so that there is no tendency for the germ to become attached to the shell, and therefore the egg does not require such frequent rotation.

This condition approximates the conditions when a hen is sitting on her eggs, for a hen never sits directly upon the top of her eggs; for when she is on the nest, her breast bone separates the eggs, so that it is the side of each egg which is in contact with her body, which portion consequently receives the direct heat.

Suitable means are provided for the admission of air by means of the openings 22, although these openings may be located at a lower portion of the casing, or in fact at any portion, if desired. For the purpose of allowing the air to escape from the upper portion of the incubator, a slot 23 is provided through which the air may escape.

When the incubator is in assembled condition, the halves 8 and 9 thereof will be separated by the heat radiating device, and the shelves will extend inwardly to a point adjacent the heat radiating device so that the eggs upon each shelf will roll into contact therewith. By having the shelves slanting, the eggs will at all times tend to be in contact with the heat radiating device. It will also be clear that either half 8 or 9 of the incubator may be lowered from its vertical position, without reference to the other half of the incubator, so that one half of the incubator may be stocked with eggs, independent of the other portion of the incubator, thereby making it possible to run the eggs in one half independent of the period of incubation of the eggs in the other part

35 of the incubator. Furthermore, each shelf holding a definite number of eggs, and the chickens, when hatched, being unable to get away from such shelf, it will be possible to tell quite definitely the chickens which come from a given number of eggs. In this way, it will be possible to keep track of the pedigree of the chickens which are being hatched. It will be noted that the shelves slant downwardly toward the heating device, so that the eggs upon the shelves will come against the heater and be held in that position, due to gravity, which is a vast improvement over any device to hold the eggs in contact with the heater.

50 Having thus described my invention, what I claim is:

1. In an incubator, a casing, a heating device within the casing, and means for supporting a plurality of eggs within the casing and against the heating device whereby each and every egg receives heat by contact with the heating device.

2. In an incubator, a casing, a heating device within the casing, a plurality of slanting shelves within the casing adapted to support the eggs; said shelves have their lower edges adjacent to the heating device whereby each egg on each shelf gravitates toward the heating device and receives heat by contact with the heating device.

3. In an incubator, a casing, a heating device within said casing, and means for supporting separate rows of eggs in contact with the wall of the said heating device whereby the eggs will be maintained in contact with the heating device at substantially a single point of contact. 70

4. In an incubator, a casing, a vertical heating device within said casing, a slanting shelf upon which the eggs are supported, and in contact with the heating device, and means carried by the shelf for turning the eggs. 75

5. In an incubator, a casing, a vertical heating device therein, a slanting shelf upon which the eggs are supported and in contact with the heating device, and a sleeve of flexible material enveloping said shelf, the eggs resting upon said sleeve. 80

6. In an incubator, a pair of shelves arranged one above the other, a curtain supported by the upper shelf and extending toward the lower shelf, and a sleeve or endless belt surrounding the shelf and curtain carried thereby. 85

7. In an incubator, a plurality of shelves, a piece of flexible material fastened at its edge to each shelf and depending therefrom, and a sleeve or endless belt surrounding each shelf and curtain. 90

8. In an incubator, the combination of a slanting shelf for supporting eggs and a guard rail, said guard rail being provided with end pieces, studs upon the end pieces, slots formed in the shelf adapted to be engaged by the studs for holding the guard rail in place. 100

9. In an incubator, a casing, a shelf within said casing, a guard rail upon the shelf, said guard rail being provided with studs at opposite ends thereof, there being slots in the shelf at the opposite ends with which said studs are adapted to engage, the said studs being slidable in the slots, the said guard rail being held by the studs from movement upon the shelf when the shelf is in its position in the casing. 105

10. In an incubator, a casing, comprising a base and portions pivotally mounted upon said base, there being chambers inclosed by the said portions of the casing adapted to contain eggs, a heating device separating the chambers in each of the said pivoted portions, whereby one of the portions of the casing may be moved away from the heating device, while the other portion of the casing remains adjacent thereto. 115

11. In an incubator, a casing comprising a base and an upper portion, said upper portion being divided longitudinally thereof, each part of the said upper portion of the casing being hingedly secured to the base, and a heating device extending between the two halves of the upper casing. 120

12. In an incubator, a casing comprising 125

a base and an upper portion, said upper portion being divided longitudinally thereof, a heating device supported by the base extending between the parts of the upper portion, and means for supporting eggs in contact with the said heating device.

13. In an incubator, a casing comprising a base and an upper portion, said upper portion being divided longitudinally thereof, a heating device fixedly supported between the divided parts of the upper portion, and slanting shelves supported in each part of the upper portion of the casing, whereby the eggs are kept in contact with the heating device.

14. In an incubator, a casing, a heating device within said casing, slanting shelves adjacent said heating device for supporting the eggs, the said shelves slanting toward the heating device whereby the eggs upon the shelf are maintained in contact with the heating device by their own gravity.

15. In an incubator, a casing, a heating device within said casing, the casing being

removable with respect to the heating device, shelves within the casing adjacent the heating device whereby the eggs contact with the heating device, said shelves slanting toward the heating device, and means associated with the shelves for preventing the eggs from rolling therefrom when the casing and heating device are moved apart.

16. In an incubator, a casing, said casing being formed with two compartments, a heating device supported within the casing between the two compartments, a series of slanting shelves in each of said compartments, the said shelves slanting toward the heating device, whereby the eggs will be maintained in contact with the heating device at substantially a single point of contact.

In testimony whereof, I hereunto affix my signature in the presence of two witnesses.

RALPH R. ROOT.
